W. L. ECKHARDT

RADIO REPRODUCER

Filed July 9, 1926

UNITED STATES PATENT OFFICE.

WALTER L. ECKHARDT, OF PHILADELPHIA, PENNSYLVANIA.

RADIOREPRODUCER.

Application filed July 9, 1926. Serial No. 121,350.

This invention relates to radio reproducers and it has for its general object to provide a novel construction of reproducer including means whereby a more accurate reproduction of sounds, whether musical or otherwise, is effected than has heretofore been practical.

It also is an object of the invention to provide a reproducer of novel construction including a plurality of independent vibratory elements adapted to be arranged and united in such relation to each other that they cooperate to reproduce accurately the various modulations of vibrations due to sound waves, whether the sound be musical or of any other character.

A further object of the invention is to provide a radio reproducer comprising a plurality of independent but operatively related conical members mounted within and cooperating with a resonant member to accurately reproduce sounds, musical or otherwise.

Another object of the invention is to provide a central conical floating vibratory member surrounded by a plurality of similar conical vibratory members, the latter being connected with the former and also having connection with and being supported upon a resonant member, preferably of drum-shape.

To these and other ends the invention comprehends the construction and arrangement of parts as hereinafter described in detail, particularly pointed out in the claims and as illustrated in the accompanying drawing, in which I have illustrated one form of a convenient embodiment of the invention.

40 In the drawing:

Fig. 1 is a view in front elevation of a reproducer embodying the invention, with the closure mounted within the end of the drum-shaped portion of the resonant member removed;

Fig. 2 is a central vertical sectional view of the said reproducer;

Fig. 3 is a view in rear elevation of a fragmentary portion of the diaphragm and

of the drum-shaped portion of the resonant member; and

Fig. 4 is a view in section of the apical portion of the diaphragm, the said section being taken in a plane coincident or parallel with the axis of the said diaphragm and the parts illustrated being shown in spaced relation with respect to each other ready to be assembled.

Referring to the drawing, 1 designates a base of relatively large dimensions upon which is mounted a pedestal-like portion 2 upon which the drum-shaped portion 3 of the resonant member is mounted. Both of the parts 1 and 2 preferably consist of wood. The drum-shaped portion 3 preferably consists of wood which may be built up of thin sheets, in known manner. Mounted within the drum-shaped portion 3 at one end is a wooden sheet 4 constituting a sounding board for the reproducer. The sheet 4 is seated against an inner rim 5 mounted within the drum-shaped portion 3 adjacent one end thereof. The sounding board sheet 4 is provided with a central opening 6, as shown in Fig. 2 of the drawing.

The opposite end of the portion 3 is provided with a closure 10 of suitable fabric provided at its periphery with a wire rim 11, by means of which the closure 10 is held in place within the portion 3 against an inner rim 12, in known manner.

The vibratory diaphragm comprises a central conical vibratory member 15 which is surrounded by a plurality of relatively small conical members 16. The latter, in the construction shown, are located in contact with each other and are fastened together at their outer adjoining edges by means of clips 17 and they are also fastened at the inner sides of their outer ends 90 by means of clips 18 to the outer end of the central conical member 15 with which they are in contact. The several vibratory conical members 15 and 16 converge from an intermediate region of the portion 3 of the resonant member toward one end of the latter and toward the axis thereof. The vibratory conical members 16 are each provided

ed with narrow extensions or tabs 20 at their outer ends and at their outer sides which are seated against the inclined edge surface 21 of the rim 22 mounted within 5 the portion 3 in a plane intermediate the opposite ends of the said portion.

In the construction as shown, the said rim is located about midway between the opposite ends of the said portion. The tabs 10 or extensions 20 may be secured to the inclined edge surface of the rim 22 by means of a suitable glue or cement, or otherwise, as may be preferred. The outer ends of the vibratory conical members 16 are connected, 15 as already stated, to the outer end portion of the vibratory conical member 15 by means of clips 18.

The small convergent ends of the vibratory conical members 15 and 16 are secured 20 together by means of conical-shaped binding members 23 and 24, the former being located within the end of the conical member 15, while the latter is located outside of the convergent ends of the conical member 16. The 25 members 23 and 24 are provided with holes 25 extending therethrough in alignment with the axes thereof, as shown. The members 23 and 24 are placed in position, as indicated in Figs. 2 and 4, and the holes there- 30 through are coincident with a hole 26 ex- tending through the small end of the conical member 15. A headed fastening member 28 extends through the said holes and the convergent small ends of the conical members 35 16 rest against the said member 28 underneath the head thereof, as is clearly indicated in Fig. 2 of the drawing. The convergent small end portions of the conical vibratory members 16 and the walls of the 40 small end portion of the conical member 15 are bound and held between the clamping members 23 and 24. The clamping and holding action of the said members is effected by means of the headed holding member 28. 45 The clamping action is effected by means of a nut 30 which engages the screw-threaded inner end of the said holding member 28. When the said nut is tightened the members 23 and 24 are drawn together and clamping 50 action thereof operates to flatten the small end portions of the vibratory conical mem- bers 16, as is clearly shown in Fig. 2 of the drawing.

The small end portion of the diaphragm 55 projects through the opening 6 in the sounding board 4, as shown in Fig. 2. The holding member 28 is provided with an axial hole extending therethrough within which one end of a reed 32 is fastened by means of a binding screw 33. The opposite end of the 60 said reed 32 is connected to the vibratory element, not shown, of a loud speaker unit 35 mounted upon a bar 36 which extends diametrically of the portion 3 of the reso- 65 nant member. The said bar 36 is secured

at its opposite ends to the rim 22, previously referred to. Current is supplied to the loud speaker unit 35 by means of a conductor 37.

In the operation of the reproducer the vibratory element of the loud speaker unit 70 35 is placed in vibration under the influence of the waves due to musical sounds or sounds of other character and these vibrations are transmitted through the reed 32 to the conical vibratory members 15 and 16. The latter 75 members are thereby caused to vibrate and the vibrations thus produced are transmitted to the resonant member or unit of the structure by which amplification is effected.

The cone-shaped vibratory members to a 80 certain extent are independent of each other and may consist of sheets of material of different thicknesses. In consequence of this a reproducer may be constructed in which the vibratory diaphragm thereof is particularly 85 adapted for the reception of sounds having certain characteristic tonal qualities. The diaphragm is of multiplex character and consequently may be so constructed as to meet the needs and requirements for repro- 90 ducing musical compositions having different characteristic qualities.

The vibratory motions of the conical mem- bers 15 and 16 are transmitted to the resonant member including the drum-shaped 95 portion 3 and the sounding board 4. As a result of the spaces between the conical mem- bers 16 and the conical member 15 and be- 100 tween the said conical members and the drum-shaped portion 3 of the resonant mem- ber means is provided whereby the sound vibrations emanating from the sounding board 4 are permitted to move readily past the said conical members 15 and 16 constituting the vibratory diaphragm of the struc- 105 ture.

Having thus described my invention, what I claim and desire to secure by Letters Patent is:

1. In a radio reproducer, the combination 110 of a resonant member comprising a drum- shaped portion and a sounding board se- cured thereto, a plurality of hollow cone- shaped members mounted upon the said drum-shaped portion and radiating from a 115 point adjacent the center of the said sound- ing board toward the opposite end of the said drum-shaped portion.

2. In a radio reproducer, the combination 120 of a resonant member comprising a drum- shaped portion and a sounding board secured to one end thereof, a diaphragm mounted within the said drum-shaped portion, said diaphragm consisting of a plurality of hol- 125 low cone-shaped members, and means for connecting the said diaphragm to the said drum-shaped portion in a plane located about midway between the opposite ends of the said drum-shaped portion.

3. A radio reproducer comprising, in com- 130

bination, a diaphragm consisting of a central hollow cone-shaped member, a series of hollow cone-shaped members surrounding the said central cone-shaped member and having connection therewith, a drum-shaped member surrounding the said diaphragm, and means for mounting the said series of cone-shaped members upon the said drum-shaped member.

10 4. A radio reproducer comprising a dia-

phragm including a floating central hollow conical member and a series of hollow conical members arranged in concentric relation to the said floating hollow conical member.

15

In testimony that I claim the foregoing as my invention, I have hereunto signed my name this 2nd day of July, A. D., 1926.

WALTER L. ECKHARDT.
